DROP PIT APPARATUS

Christopher H. Schramm and Lloyd H. Holdeman,
Muskegon, Mich., assignors to Manning, Max-
well & Moore, Inc., Muskegon, Mich., a corpo-
ration of New Jersey

Application June 21, 1946, Serial No. 678,348

17 Claims. (Cl. 104—32)

1

The invention relates to drop pit apparatus of the type commonly used in railroad shops for removing and replacing the trucks or wheels of locomotives and other vehicles and for transporting the trucks and wheels between the various service tracks of the shop.

One object of the invention is to provide apparatus of the above general character having a light duty elevator mechanism for raising and lowering the truck supporting table between track level and transporting positions and a heavy duty elevator mechanism for raising the table above track level to lift a vehicle or to compress the springs thereof preparatory to removing or replacing the trucks or wheels whereby each elevator mechanism may be designed and constructed for the most efficient performance of its duties so as to provide maximum power when required with high operating speeds when such are desirable, greater accuracy in the control of the mechanism of table movements, and a material reduction in the overall cost of the apparatus.

A more specific object is to provide heavy duty table elevator mechanism for drop pit apparatus which is operative to provide the powerful thrust required for raising a heavy vehicle or for compressing the springs to permit removal of a set of wheels, thereby permitting use of a lighter weight and higher speed elevator mechanism for raising and lowering the table from the track level to the transporting position.

Another object is to provide hydraulically operated table elevator mechanism for drop pit apparatus adapted to supplement the main elevator mechanism and to supply the powerful thrust required for certain types of work, thus leaving the main elevator mechanism to the performance of its normal function of raising and lowering the table between track level and transporting positions.

Other objects and advantages of the invention will become apparent from the following detailed description of the preferred embodiment illustrated in the accompanying drawings in which:

Figure 1 is an end elevational view of drop pit apparatus embodying the features of the invention.

Fig. 2 is a side elevational view of the apparatus.

Fig. 3 is a detail view of the means for connecting and disconnecting the table and the auxiliary elevator mechanism.

Figs. 4 and 5 are fragmentary side elevational views showing the different positions of the heavy duty auxiliary elevator mechanism.

2

Fig. 6 is a fragmentary side elevational view showing the table in course of being lowered by the light duty elevator mechanism.

Fig. 7 is a diagrammatic view showing the hydraulic circuit for the heavy duty auxiliary elevator mechanism.

While the invention is susceptible of various modifications and alternative constructions, we have shown in the drawings and will herein describe in detail the preferred embodiment, but it is to be understood that we do not thereby intend to limit the invention to the specific form disclosed, but intend to cover all modifications and alternative constructions falling within the spirit and scope of the invention as expressed in the appended claims.

For purposes of illustration the invention has been shown as incorporated in apparatus for use in a pit 10 which intersects and extends beneath one or more railroad tracks T, commonly called service or repair tracks. In order to permit locomotives or other vehicles to be run over the pit, drop tables 11 are provided for bridging the pit at the various service and repair tracks. The tables 11 may be of the general type shown in the Minty Patent No. 2,111,917, granted March 22, 1938, each comprising a generally rectangular frame adapted to be releasably supported in pit bridging position by retractable latch bars 12 engaging ledges 13 in the side walls of the pit. Rails 14 carried by the table are aligned with the rails of the service track T thus forming an extension of such track when the table is latched in place across the pit.

Means is provided for raising and lowering the drop table 11 and for transporting it along the pit 10 for association with any of the various service and repair tracks in the shop. Such means comprises a carriage 15 having an elevator table 16 supported and guided thereon for vertical movement by upright columns 17 extending upwardly from the carriage to a point closely adjacent the top of the pit. The carriage is fitted with flanged wheels 18 adapted to run on rails 19 forming a track at the bottom of the pit. Suitable means such as an electric motor M is provided for driving the carriage and its load along the track.

When a set of wheels is to be removed from a vehicle, as for example the drivers of a locomotive, the drop table 11 is latched in pit bridging position at one of the service tracks T and the locomotive is run over the pit so as to spot the drivers on the table track section 14. To facilitate the disconnection of the drivers from the

locomotive it is usually necessary to compress their springs and thus relieve the pressure on the retaining bolts. This is done by raising the table 11 and the drivers spotted thereon a short distance above track level. A relatively small vertical movement is sufficient for this operation but it will be evident that a relatively heavy thrust is required to produce it.

Upon their disconnection from the locomotive, the drivers are supported by the table 11 and may be lowered with it until they clear the running gear of the locomotive and any drop tables bridging the pit at other service tracks. With the table in such lowered or transporting position the carriage 15 is traversed along the pit to another service track and the drop table raised to track level to permit the drivers to be rolled off for repairs or other attention. To replace a set of drivers the sequence of operations above described is simply reversed.

In accordance with the invention, separate elevator mechanisms are provided for traversing the elevator table 16 in each of the two ranges of travel above referred to, each such mechanism being designed and constructed to most efficiently meet the operating requirements of its particular range. Thus for raising and lowering the table between a transporting position within the pit and the track level position, in which range only the weight of the table and its load is involved, we provide a light duty elevator mechanism capable of traversing the table at high speed through a relatively long range of travel. For traversing the table in the range for lifting vehicles or for compressing their springs, we provide heavy duty elevator mechanism constructed and arranged to exert the heavy thrust required for that purpose. Moreover, provision is made for rendering each mechanism effective automatically in its own range of travel thus whereby simple, safe and foolproof control of the operation is insured.

The light duty elevator mechanism may be of any preferred type such, for example, as that disclosed in the Blake Patent No. 1,849,972, granted March 15, 1932, which has been found particularly suitable where high operating speeds and a long range of travel is required. As shown in Fig. 2 of the drawings, the mechanism comprises generally a series of flexible cables 20, preferably in the form of flat wire ropes, by which the table 16 is suspended from the upper ends of the columns 17. One of the cables 20 is anchored to each column and is extended over a rounded guide member 21 adjacent the upper end of the column to a drum 22 rotatably mounted on the table 16. Thus by winding the cables 20 on or unwinding them from the drums 22 the table may be raised or lowered as required. Power actuated means herein shown as an electric motor M1 is provided for driving the drums 22.

The heavy duty elevator mechanism comprises generally a plurality of actuator members, herein shown as push rods 25, each supported on one of the columns 17 for vertical movement toward and from the table 16. While any suitable power actuated means may be utilized for actuating the push rods, hydraulically operated actuators are preferred. In the exemplary apparatus, the push rods 25 are accordingly provided with pistons 26 working in cylinders 27 as shown in Fig. 7. One such cylinder 27 is rigidly secured to each column 17 adjacent the lower end of the column and the associated push rod 25 extends upwardly

along the side of the column through suitable guides 28 secured thereto.

Means is provided for operatively connecting the push rods 25 and the table 16 as the latter approaches its upper or track level position and for automatically interrupting the connection when the table is lowered from such position by the main elevator mechanism. The connecting means as herein shown comprises a series of abutment members 30 carried by the table 16 and adapted to be interposed between the framework of the table and the upper ends of the respective push rods.

Referring to Figs. 1 and 3 of the drawings, the members 30, herein shown as elongated flat steel bars, are suspended from the table 16 to swing into or out of the path of movement of the push rods. For this purpose each member is provided with two laterally projecting arms 31 spaced apart longitudinally of the member to straddle one of the beams constituting the framework of the table. At their outer ends the arms 31 are formed with elongated apertures 32 for the reception of pivot pins 33 carried by the table to provide for limited vertical movements of the abutment member in addition to swinging movement about the pins 33 as an axis.

Mounted on the underside of the table 16 above each of the abutment members 30 are a pair of guide blocks 34 having downwardly facing rectangular notches 35 dimensioned for the reception of the member and substantially aligned with the axis of the push rod 25. As will be seen by reference to Fig. 3, the upper end portions of the arms 31 are inclined so as to overlie the abutment member 30 and the apertures 32 are aligned in a common vertical plane with the notches 35, the central axis of the abutment member and the associated push rod 25. Accordingly, when unrestrained, the abutment members automatically swing between the guide blocks and the adjacent ends of their associated push rods in alignment with the notches 35.

By reason of the lost motion connection provided by the slots 32, the abutment members are free to move upwardly when engaged by the push rods in their upward movement. When the members engage the guide blocks as shown in Fig. 4 the thrust of the rods is transmitted to the table to raise the same above track level position as shown in Fig. 5. The abutment members, of course, engage in the notches 35 in the blocks and are thus effectually held against displacement from operative position while the table is supported by the push rods.

Provision is made for swinging the abutment members 30 into or out of operative position in accordance with the position of the elevator table 16 whereby to render the heavy duty elevator mechanism operative for raising the table above the track level position and to render the mechanism inoperative in the travel range of the main elevator mechanism. As herein shown, the means provided for controlling the operativeness of the abutment members comprises a series of cams, one for each abutment member, adapted for cooperation with follower rollers 37 (Fig. 3) mounted on the outer supporting arm 31 of each member.

The cams may be conveniently formed on one of the side webs of each of the columns 17 and, as herein shown, each comprises an upper vertical section 38 (Figs. 2, 3 and 6) disposed so as to allow the abutment member to swing into operative position as the table 16 is raised to the track level position. At the lower end of the cam sec-

tion 38 is an inclined section 39 adapted to swing the abutment member outwardly to the inactive position shown in Fig. 6 as the table is lowered from the track level position and a vertically disposed intermediate section 40 for holding the member in such position during the lowering of the table. At its lower end the intermediate cam section is connected by a second inclined section 41 with a vertically disposed section 42 offset further to the right (as viewed in Fig. 6) for swinging the abutment member outwardly to clear the cylinder 27 as the table approaches the carriage.

In order to maintain the table level while being raised or lowered by the heavy duty elevator mechanism the actuators for the push rods 25 are constructed and arranged for operation at the same rate of speed. Thus, when hydraulically operated actuators are used as in the exemplary apparatus, pressure fluid is supplied to each of the cylinders 27 so as to exert equal pressures on the pistons 26 and thereby generate an equal thrust through each of the rods 25. For this purpose the cylinders are connected in multiple as shown in Fig. 7 to receive pressure fluid from a common pump P under control of a suitable manually operable valve V. The control valve V is arranged to connect the cylinders 27 simultaneously with the pump for raising the table or with a drain 45 for returning the pressure fluid from the cylinders to a sump or reservoir R from which it may be withdrawn by the pump for reuse. When the cylinders are connected to the drain, the tables 14 and 16 descend by gravity. The rate of such descent is regulated by adjustment of the control valve. The pump P, which may be of any preferred type, together with a motor M2 for driving it and the reservoir R are suitably supported on the carriage 15.

In the operation of the improved drop pit apparatus a vehicle is run over the pit 10 so as to spot the wheels to be serviced on the table track section 14, the drop table 11 being supported in pit bridging position by the latches 12 at such time. The carriage 15 is traversed along the pit track 19 to locate it below the drop table and the light duty elevator mechanism is operated to raise the elevator table 16 into close proximity to the drop table. When the vehicle wheels can be disconnected without compression of their springs the heavy duty elevator mechanism is used only to raise the table sufficiently to relieve the latches 12. Upon disconnection of the wheels the drop table is released from the pit by withdrawal of the latches 12 and may then be lowered into the pit by the light duty elevator mechanism. The wheels may be transported along the pit and transferred to another service track in accordance with the usual practice.

Where it is necessary to compress the vehicle springs to permit removal or replacement of a set of wheels, the elevator table 16 is raised into engagement with the drop table 11 as above described to support the latter upon withdrawal of the latches 12. As the table approaches the track level position in which it is shown in Fig. 1, the abutment members 30 swing into alignment with the piston rods 25 and thus condition the heavy duty elevator mechanism for operation. Suitable control means such as a limit switch (not shown) may be provided for interrupting the operation of the light duty elevator mechanism when the table reaches track level position and for preventing further operation of that mechanism in a table raising direction.

Operation of the heavy duty elevator mecha-

nism is initiated by manually setting the control valve V to direct pressure fluid from the pump P to the lower ends of the cylinders 27. It will be appreciated that the valve V may be adjusted so

- 5 as to control the rate of fluid flow to the cylinders thus providing for accurate regulation of the rate of table movement. The delivery of pressure fluid to the cylinders 27 forces the pistons 26 and their associated push rods 25 upwardly.
- 10 A slight movement of the push rods carries them into engagement with the abutment members 30 which move upwardly with the rods to engage the guide blocks 34 and thus transfer the thrust of the rods to the elevator table 16. Continued upward movement of the push rods raises the elevator table 16 together with the drop table 10 and the vehicle wheels spotted thereon thus compressing the vehicle springs so that the wheels may be disconnected from the vehicle. Engagement of the abutment members 30 in the notches 35 of the guide blocks effectually prevents accidental displacement of the abutment members while the drop table is supported by the heavy duty elevator mechanism.
- 15 After disconnection of the wheels from the vehicle the control valve V is operated to connect the cylinders 27 to the drain 45 thereby permitting the pistons 26 and the associated apparatus including the drop table to descend by gravity.
- 20 When the slack is taken up in the cables 20 substantially as the table reaches track level position, the load is transferred to the cables of the light duty elevator mechanism which may then be operated in the usual manner to lower the drop table into the pit. The heavy duty elevator mechanism is automatically rendered ineffective during such lowering action. After the support of the table is transferred to the cables 20, the push rods 25 are withdrawn to their retracted or idle positions as shown in Fig. 3. Upon such withdrawal the abutment members 30 drop out of the notches 35 and hang freely from the pins 33. As the table is lowered by the light duty elevator mechanism the cam surfaces 39 and 40 swing the abutment members outwardly clear of the push rods 25 as shown in Fig. 6 and maintain them in such positions until the table is again raised to track level.

45 It will be apparent from the foregoing that the invention provides drop pit apparatus capable of performing the various operations commonly required of such apparatus with a high degree of efficiency. Heavy duty elevator mechanism supplies the powerful thrust required for raising a vehicle or for compressing the springs thereof, thus permitting the use of high speed light duty elevator mechanism for raising and lowering the elevator table within the pit. Control of the apparatus for the different operations is simple and foolproof and any possibility of interference between the two elevator mechanisms is precluded by the provision of means for conditioning each mechanism for operation only in its proper range of travel.

60 65 We claim as our invention:

1. In a drop pit apparatus, a carriage adapted to traverse a pit extending beneath a service track, a table supported on said carriage, light duty elevator mechanism mounted on said table for raising and lowering the table through a predetermined range of travel, and heavy duty elevator mechanism mounted on said carriage for raising the table independently of said light duty mechanism through a different range of travel.
- 70 75 2. In a drop pit apparatus, a carriage adapted

to traverse a pit extending beneath a service track, a table supported on said carriage, light duty elevator mechanism mounted on said table for raising and lowering the table through a predetermined range of travel, separate independent heavy duty elevator mechanism mounted on said carriage for raising the table through a different range of travel, and means operative at a selected point in the predetermined range of travel of the table for rendering said heavy duty mechanism effective.

3. In a drop pit apparatus, a carriage adapted to traverse a pit extending beneath a service track, a table supported on said carriage, light duty elevator mechanism mounted on said table for raising and lowering the table through a predetermined range of travel, heavy duty elevator mechanism mounted on said carriage for raising the table through a different range of travel, and cam controlled means on said carriage for rendering said heavy duty mechanism effective at a selected point in the predetermined range of travel of the table.

4. Drop pit apparatus comprising, in combination, a carriage adapted to traverse a pit located below a service track, a table supported on said carriage, elevator mechanism mounted on said table for raising and lowering the table through a predetermined range of travel, independent auxiliary elevator mechanism mounted on said carriage for raising and lowering the table through a different range of travel, and members carried by said table providing a disengageable connection between the table and said auxiliary elevator mechanism.

5. Drop pit apparatus comprising, in combination, a carriage adapted to traverse a pit located below a service track, a table supported on said carriage, mechanical elevator mechanism including power means mounted on said carriage for raising and lowering said table between a track level position and a position in which the table rests directly on said carriage, and hydraulically operated elevator mechanism mounted on said carriage for lifting the table above said track level position.

6. In drop pit apparatus, a carriage, a plurality of upright columns mounted on said carriage, a table supported on said columns, elevator mechanism mounted on said table coacting with means on said carriage for raising and lowering the same between lower and upper limit positions, and other elevator mechanism mounted on said columns for raising and lowering the table above said upper limit position.

7. In drop pit apparatus, in combination, a carriage, a table, means supporting said table on the carriage, said supporting means being operable to raise and lower the table through a predetermined range of travel, and means including a plurality of hydraulically actuated push rods mounted on said carriage for raising and lowering the table through a different range of travel.

8. Drop pit apparatus comprising, in combination, a carriage, upright columns mounted on said carriage, a table, flexible cables connected to the upper ends of said columns, winding drums mounted on said table, said cables being connected to said drums to support the table on said columns, power operated means mounted on said table for driving said drums to wind up and unwind the cables and thus raise and lower the table, and heavy duty elevator mechanism carried by the carriage and adapted to raise and

lower said table independently of said cable and drum means.

9. In drop pit apparatus of the character described, in combination, a carriage, a table, means supporting said table on said carriage operable to raise and lower the table through a predetermined range of travel, lifting devices mounted on said carriage, and means carried by said table adapted to provide an operative connection between the table and said lifting devices as the table approaches the upper end of its predetermined range of travel.

10. In drop pit apparatus of the character described, in combination, a carriage, a table, means including a vertically movable actuator member supported on the carriage, means supporting said table on said carriage for movement vertically relative to said actuator member through a predetermined range of travel, a plurality of vertically shiftable hydraulically actuated push rods mounted on said carriage, and means operable as the table approaches the upper end of said predetermined range of travel for rendering said push rods effective for raising and lowering the table through a range of travel above said predetermined range.

11. In drop pit apparatus of the character described, in combination, a carriage, a table, means supporting said table on said carriage operable to raise and lower the table through a predetermined range of travel, power actuated lifting devices mounted on said carriage, members on said table adapted to provide an operative connection between the table and said lifting devices, said members being movable to inactive positions to interrupt said connection, and means for shifting said members to their inactive positions in response to the downward movement of the table.

12. In drop pit apparatus of the character described, in combination, a carriage having a plurality of upright columns mounted thereon, an elevator table, means supporting said table on said columns, said supporting means being operable to raise and lower the table through a predetermined range of travel, auxiliary table elevating means for raising and lowering the table through a different range of travel including push rods supported on the carriage for movement vertically toward and from the table, said table being operative to clear said push rods when within said predetermined range of travel, and members pivotally supported on said table to swing between the table and the adjacent ends of said push rods whereby to establish an operative connection therebetween, said push rods being normally spaced from said members to permit the swinging of the members between active and inactive positions.

13. In drop pit apparatus of the character described, in combination, a carriage, an elevator table, means supporting said table on said carriage, said supporting means being operable to raise and lower the table through a predetermined range of travel, auxiliary means for raising and lowering the table through a different range of travel including push rods supported on said carriage for movement vertically toward and from the table, a pressure fluid operated actuator for each push rod, a source of fluid under pressure, and a single valve for controlling the delivery of pressure fluid from said source to each of said actuators.

14. In drop pit apparatus of the character described, in combination, a carriage, a plurality

of upright columns on said carriage, a table, means supporting said table on said columns, said means being operable to raise and lower the table through a predetermined range of travel, auxiliary elevator means including a cylinder rigidly secured to each column, a piston in each cylinder, a push rod extending upwardly from each piston along one side of the associated column, means for supplying pressure fluid to the cylinder to shift the piston and associated push rod upwardly, a plurality of abutment members mounted on said table for movement into or out of operative relation to said push rods, and cam means on said columns controlling the movements of said members.

15. In drop pit apparatus of the character described, in combination, a carriage, a plurality of upright columns on said carriage, a table, means supporting said table on said columns, said means being operable to raise and lower the table between lower and upper limit positions, auxiliary table elevating means including an actuator rigidly secured to each column, a push rod extending upwardly from each actuator along one side of the associated column, a plurality of abutment members pivotally supported on the table and adapted to swing into the paths of the push rods as the table approaches its upper limit position, said push rods being operable through said members to raise the table above said upper limit position, and cam means on said columns operative to swing the members out of the paths of the push rods when the table is lowered from said upper limit position.

16. In drop pit apparatus of the character described, in combination, a carriage, elevator mechanism mounted on said carriage including a plurality of vertically movable push rods, a table movable longitudinally of said push rods and having openings providing clearance for the rods, guide blocks secured to the underside of the table on opposite sides of the openings, said guide blocks having downwardly opening notches

- in their lower faces, and pivotally supported abutment members adapted to swing between the upper ends of the push rods and the associated guide blocks when the table is raised above the push rods, said members having a lost motion connection with the table to permit movement of the members into the notches in said guide blocks upon engagement of the members by the push rods in their upward movement.
- 10 17. In drop pit apparatus of the character described, in combination, a carriage, elevator mechanism mounted on said carriage including a plurality of vertically movable push rods, a table movable longitudinally of said push rods and having openings providing clearance for the rods, guide blocks secured to the underside of the table on opposite sides of the openings, said guide blocks having downwardly opening notches in their lower faces, abutment members movable between the upper ends of the push rods and the associated guide blocks when the table is raised above the push rods, and means providing a lost motion connection between the table and said members to permit the members to move upwardly with the push rods and engage in said notches, said notches preventing withdrawal of the abutment members while said elevator mechanism is in operation.
